John Tracy, Attorney

UNITED STATES PATENT OFFICE.

COVERT R. SMITH, OF FREEPORT, OHIO.

COMBINED IRONING-TABLE AND STEP-LADDER.

1,216,176.

Specification of Letters Patent. Patented Feb. 13, 1917.

Application filed August 5, 1915. Serial No. 43,807.

To all whom it may concern:

Be it known that I, COVERT R. SMITH, a citizen of the United States, residing at Freeport, in the county of Harrison and 5 State of Ohio, have invented certain new and useful Improvements in Combined Ironing-Tables and Step-Ladders, of which the following is a specification.

My invention relates to new and useful 10 improvements in convertible step ladders and ironing tables, the primary object of my invention being the provision of a device of the above described character which, when not in use for either purpose, may be 15 folded into compact form and which will be rigid and strong either when used as a step ladder or as an ironing table.

In this connection, I construct a step ladder having swingingly connected front and 20 rear frame members, the front frame member being formed in upper and lower hingedly connected portions each of which is provided with certain of the steps making up the ladder and the upper portion of 25 which also carries the ironing board.

In connection with the above structure, a 30 still further object of my invention consists in the provision of means for automatically locking the ironing board to the lower portion of the forward frame member when the frame members are in alinement with each other with the result that the ironing board is not only held against displacement, when the device is used as a step ladder, but also 35 with the result that the locking of the ironing board serves to lock the portions of the forward frame member together and in alinement with each other.

In this connection, a still further object 40 of my invention consists in the provision of means for automatically locking the lower portion of the forward frame member to the intermediate portion of the rear frame member when the device is in use as an ironing table this, as a result, also locking 45 the ironing board in horizontal position and against movement.

In this connection, my invention further 50 comprehends a simple and effective releasing mechanism for springing the rear frame member out of engagement with the lock of the lower portion of the forward frame member in order that the device may be folded when not in use.

55 With these and other objects in view, my invention will be more fully described, illus-

trated in the accompanying drawings, and then specifically pointed out in the claims which are attached to and form a part of this application.

60 In the drawings:

Figure 1 is a perspective view of my improved ladder and ironing table, showing the position of the parts when the device is used as a step ladder;

Fig. 2 is a central vertical sectional view 65 of the device in the position shown in Fig. 1;

Fig. 3 is a perspective view of the device used as an ironing table;

Fig. 4 is a central, vertical, longitudinal 70 sectional view of the device in this position.

Corresponding and like parts are referred 75 to in the following description and indicated in all the views of the drawings by the same reference characters.

Broadly speaking, my invention comprehends a rear frame member 10, a forward frame member consisting of an upper portion 11 and lower portion 12 and an ironing 80 board 13. The upper portion of the forward frame member includes parallel spaced side bars or upper legs 14 connected at their upper ends by the upper step 15 of the ladder and intermediate its length by additional steps 85 16 which project at their rear edges beyond the rear edges of the upper leg portions 14. The ironing board 13 is secured to the rear edges of the steps 16 and its upper face lies flush with the rear face of the step 15, the 90 free end of the ironing board projecting a considerable distance beyond the lower ends of the leg portions 14, which ends are preferably cut at an angle, as shown, in order to provide a neat structure when the 95 device is in use as an ironing table as will appear from Figs. 3 and 4 of the drawings. Brace blocks 17 are secured against the outer faces of the leg portions 14 and to the inner or lower face of the ironing board, and the 100 rear legs 18, constituting the chief part of the rear frame member of the ladder, are pivotally connected at their upper ends to these brace blocks, the lower end of these legs 18 being connected by a transverse 105 brace 19.

Pivot bolts 20 hingedly connect the upper ends of lower forward leg portions 21 to the lower ends of the forward leg portions 14, the pivotally connected ends of such leg portions overlapping each other with the lower forward portions outside of the upper leg 110

portions in order that the lower part of the ladder may be wider than the upper portion to give it a more firm foundation. These lower leg portions also carry and are 5 braced by a plurality of steps or treads 22 corresponding to the steps or treads 16 and extending at their rear edges beyond the rear edges of the legs 21. The lower legs 21 are also preferably braced adjacent their 10 lower ends by crossed diagonal braces 23 and the lower forward leg portions are connected to the rear legs 18 by hinge braces 24 pivoted at their ends to the forward and rear legs and hinged intermediate their 15 length, as shown at 25, to break upwardly.

In order to hold the upper and lower portions of the forward frame member in alignment with each other, both when the device is not in use and when it is being employed 20 as a ladder, I provide a keeper strip 26 which is secured transversely to that face of the ironing board adjacent the steps of the ladder near the free end of the ironing board and in such a position and at such an 25 angle as to swing directly beneath the lowermost step 22 when the forward frame members or portions are in alignment with each other, as shown in Fig. 2. The upper face of the lowermost step 22 is formed 30 throughout its length with a groove or channel 27 in which seats a spring bar 28, either of wood or resilient metal which carries, intermediate its length, a locking pin 29 adapted to engage in an opening 30 formed 35 in the keeper bar 26, being forced into engagement in such opening by the member 28. The member 28 is secured in place by pins or other suitable devices 31 passed through slots formed in its ends and into the 40 step 22, these slots permitting the up-bowing of the member to release the pin from the opening 30, when desired. To facilitate this releasing, the upper face of the step 22 is formed with a recess 32 communicating 45 with the intermediate portion of the channel 27 in order that the operator may readily reach under one edge of the member 28 to raise it. To facilitate the automatic engagement of the pin 29 in the opening 30, 50 the intermediate portion of the keeper plate has its upper face beveled, as shown at 33 in Fig. 2, in order that the pin may readily ride over such beveled face.

Secured to the outer faces of the lower 55 forward legs 21 are vertically spaced stop blocks 34 and 35, the latter or upper stop blocks being wedge-shaped with their inclined faces directed upwardly. As shown in Fig. 1, the hinged braces 24 are pivoted 60 against the outer faces of the lower stop blocks 34 and these braces may, therefore, swing past both stop blocks.

At this point it should be noted that 65 whether the above described article is made of wood or of metal, the rear leg portions 18

should possess sufficient resiliency to permit them to ride over the inclined upper faces of the upper stop blocks 35 in a manner which will be later more fully explained. Releasing arms 36 are pivoted to the rear 70 edge of that step 22 adjacent the stop blocks 35 and at their free outer ends are provided with cam faces 37 which, when the opposite ends of the members are swung inwardly and downwardly, will project past 75 the outer faces of the leg members 21, for a reason which will be later explained. These releasing members or arms are preferably so proportioned that before their cam heads get beyond the outer faces of the legs 21, 80 their opposite ends will overlap each other in order that pressure exerted against one of them may act equally upon both.

In describing the operation of my improved step ladder and ironing table, I will 85 first assume that the device is in compact position as it would be when not in use, will then explain the manner of employing it as a step ladder, then the manner of converting it into an ironing board, and subsequently the manner of returning it to its 90 original folded position. When not in use, the upper and lower portions of the forward frame member are locked in alignment with each other by engagement of the locking pin 29 in the keeper bar 26, in the manner shown in Figs. 1 and 2, and the rear legs 18 bear against the rear edges of the stop blocks 34 and 35, the hinged braces 24 being broken upwardly and the lower end of 95 the ironing board 13 being immediately above the cross brace 19 of the rear frame member. To utilize the device as a step ladder, it is only necessary to swing the rear legs backwardly to the position shown in 100 Figs. 1 and 2, the braces 24, of course, opening up automatically during swinging of the rear legs and ultimately locking the ladder in position. During this time, the ironing board remains locked to the lower forward 105 frame member and the inner ends of the members 36 are held against any possible outward swinging movement by stop blocks 38 secured between the lower ends of the upper leg portions 14 and the ironing 110 board 13.

If the device is to be used as an ironing board or table, and is folded, as first assumed, the first step toward bringing it into 115 condition for use consists in the above described operation of opening it up to provide a step ladder. After this operation has been completed, the latch member 28 is raised to free the ironing board from the 120 lower forward frame member when the upper frame member may be swung rearwardly upon the upper end of the rear frame member as a pivot, the intermediate portions of the rear leg members sliding 125 downwardly over the outer faces of the 130

lower forward leg members and finally over the inclined faces of the upper stop blocks 35, being spread during such movement and ultimately springing back to seat between the upper and lower stop blocks 35 and 34, in the manner shown in Figs. 3 and 4 of the drawings. When so seated, the rear frame member and lower portion of the forward frame member are rigidly locked by the 5 stop blocks and by the extended braces 24 and as a result the upper forward frame member and ironing board carried thereby are rigidly held by the upper ends of the rear frame member and lower forward frame 10 member.

To return the device to normal or folded position, from the position shown in Figs. 3 and 4, the inner ends of the levers or arms 36 are simultaneously swung downwardly 15 in order that their cam faces 37 may be swung out to engage the inner faces of the rear legs 18 to force them away from the forward legs 21 and out of engagement with the stop blocks 35. When so moved outwardly, it will be clear that the free end of the ironing board may be swung downwardly, the lower ends of the forward and rear frame members moving toward each other until the ironing board engages the 25 lowermost step 22 and is locked in position.

Although I have illustrated and described my invention in all its details of construction, it will of course be understood that I do not wish to be limited to such details as 30 various minor changes, within the scope of the appended claims may be made at any time without in the slightest degree departing from the spirit of the invention.

Having thus described the invention, what 40 is claimed as new is:—

1. A combined step ladder and ironing table including upper and lower forward frame members pivotally connected, a rear frame member pivotally connected at its 45 upper end to the upper end of the upper forward frame member, hinged braces pivotally connecting the forward and rear frame members, and an ironing board rigidly secured to one of the forward frame members 50 and detachably secured to the other forward frame member near the free end of the latter to hold the forward frame members in alignment.

2. A combined step ladder and ironing 55 table including an upper forward frame member, a lower forward frame member pivoted to the upper frame member, a rear frame member pivoted to the upper frame member, hinged braces connecting the lower 60 frame member and rear frame member, an ironing board secured to the upper frame member, locking means for detachably securing the ironing board to the lower frame member, the proportioning of the frame 65 members being such that the upper end of

the lower frame member may, upon release of the ironing board therefrom, be swung between the sides of the rear frame member to bring the upper frame member and ironing board into a horizontal position.

3. A combined step ladder and ironing table including an upper forward frame member, a lower forward frame member pivoted to the upper frame member, a rear frame member pivoted to the upper frame member, hinged braces connecting the lower frame member and rear frame member, an ironing board secured to the upper frame member, locking means for detachably securing the ironing board to the lower frame 70 member, the proportioning of the frame members being such that the upper end of the lower frame member may, upon release of the ironing board therefrom, be swung between the sides of the rear frame member to bring the upper frame member and ironing board into a horizontal position, and means for locking the parts in such position.

4. A combined step ladder and ironing table including an upper forward frame member, a lower forward frame member pivoted to the upper frame member, a rear frame member pivoted to the upper frame member, hinged braces connecting the lower frame member and rear frame member, an ironing board secured to the upper frame member, locking means for detachably securing the ironing board to the lower frame member, the proportioning of the frame members being such that the upper end of the lower frame member may, upon release of the ironing board therefrom, be swung between the sides of the rear frame member to bring the upper frame member and ironing board into a horizontal position, and spaced locking blocks carried by the lower frame member and adapted to seat the sides of the rear frame member to lock the frame members in such position.

5. A combined step ladder and ironing 110 table including an upper forward frame member, a lower forward frame member pivoted to the upper frame member, a rear frame member pivoted to the upper frame member, hinged braces connecting the lower 115 frame member and rear frame member, an ironing board secured to the upper frame member, locking means for detachably securing the ironing board to the lower frame member, the proportioning of the frame members being such that the upper end of the lower frame member may, upon release of the ironing board therefrom, be swung between the sides of the rear frame member to bring the upper frame member and ironing board into a horizontal position, spaced locking blocks carried by the lower frame 120 member and adapted to seat the sides of the rear frame member to lock the frame members in such position, and means for spring- 125

ing the sides of the rear frame member apart to free them from the locking blocks.

6. A combined step ladder and ironing table including an upper forward frame member, a lower forward frame member pivoted to the upper frame member, a rear frame member pivoted to the upper frame member, hinged braces connecting the lower frame member and rear frame member, an ironing board secured to the upper frame member, locking means for detachably securing the ironing board to the lower frame member, the proportioning of the frame members being such that the upper end of the lower frame member may, upon release of the ironing board therefrom, be swung between the sides of the rear frame member

to bring the upper frame member and ironing board into a horizontal position, spaced locking blocks carried by the lower frame member and adapted to seat the sides of the rear frame member to lock the frame members in such position, and means operable simultaneously for springing the sides of the rear frame member apart to free them from the locking blocks, said means including cam levers pivoted to the forward frame member and movable into engagement with each other whereby movement of one will cause the projection of both into engagement with the sides of the rear frame member.

In testimony whereof I affix my signature.

COVERT R. SMITH.
